UNITED STATES PATENT OFFICE.

EUGENE MOREHOUSE, OF PROVIDENCE, RHODE ISLAND, ASSIGNOR TO B. A. BAILLON & CO., INC., OF PROVIDENCE, RHODE ISLAND, A CORPORATION OF RHODE ISLAND.

SAFETY CATCH.

Application filed March 27, 1925. Serial No. 18,864.

To all whom it may concern:

Be it known that I, EUGENE MOREHOUSE, a citizen of the United States, residing at Providence, in the county of Providence and State of Rhode Island, have invented 5 certain new and useful Improvements in Safety Catches, of which the following is a specification.

This invention relates to an improved 10 construction of safety catches for pins, brooches and the like, and has for its object to provide a safety catch of this character comprising a body portion formed of a pair of ears folded up from a common base, the 15 inner surface of the ears being each provided with cooperating annular grooves in which is slidably mounted a guard member having a peripheral opening, the same being provided with an operating handle extending 20 outwardly and over laterally to engage one side of the ear portion to retain the rotor guard in operative position in its ear even though these ear members may be widely spread by some excessive strain brought to 25 bear upon them.

With these and other objects in view, the invention consists of certain novel features of construction, as will be more fully described, and particularly pointed out in the 30 appended claims.

In the accompanying drawings:

Figure 1 is a side elevation showing my improved catch as mounted on the back of a bar pin and retaining the pointed end of the 35 fastening pin-stem.

Figure 2 is a view showing this catch member as swaged from sheet stock while in extended position.

Figure 3 illustrates the ear members as 40 partially folded up from the base.

Figure 4 is a central sectional view through the base portion of the body member with the guard member removed.

Figure 5 is the same as Figure 4 with the 45 guard member mounted in the groove of the body and showing its operating handle as extending from the groove and laterally over to engage one side of the ear portion, the guard member being in open position.

Figure 6 is the same as Figure 5 showing the guard member as having been rotated to closed position.

Figure 7 is a side elevation showing the guard member as provided with an elong-

gated operating handle in extended position. 55

Figure 8 is a sectional view showing the operating handle of the guard member as folded over and about one side of one of the ear members.

Figure 9 is an edge view illustrating the 60 operating arm as extending through a slot in the back of the body and over to one side thereof about a portion of the ear to retain the guard even though the ear members may become widely separated.

This invention is an improvement on 65 prior Patent No. 1,054,701, dated March 4, 1913, both being owned by the same assignee.

It is found in the practical construction 70 and operation of safety catches of this character, of advantage to provide simple and effective means wherby the guard member is unable to become disengaged from its groove in the body of the catch, even though the ear members should become widely separated as 75

is sometimes the case when the catch has been subjected to extraordinary strains thereby preventing the release of the pin-stem and loss of the bar pin or brooch on 80 which the catch may be mounted; and to accomplish this in a simple and effective way, I have formed an operating handle on the rotor keeper, of extended length and have folded or extended the same over and around to engage one side of one of the ear 85

members so that even though these ear members should become widely separated by some undue strain at their usual meeting edges the guard member mounted therein, would be prevented from becoming disengaged from its operating position and would 90 still function to retain the pointed end of the pin-stem; and the following is a detailed description of the present embodiment of

my invention showing one means by which 95 these advantageous results may be accomplished:

With reference to the drawings, 10 designates the base of a bar pin or other form of jewelry on which the usual pin-stem 11 is mounted and 12 designates my improved safety catch which is designed to receive and retain the pointed end of this pin-stem also mounted thereon.

My improved safety catch may be formed 105 preferably of two cooperating ear members 13 connected to a common base 14. Each of these ears is provided with a radial slot 15

for the reception of the pin-stem and about the center of this slot is formed annular grooves 16 and when these ears are folded up these grooves cooperate to provide a bearing for the reception of the ring-shaped guard member 17.

In the back of these ears a slot 18 is formed which communicates with the annular groove 16 therein. This ring-shaped guard member is provided with a peripheral opening 19 which is of a size to register with the opening 15 in the ears to permit of free entrance of the point of the pin-stem thereto. This guard member is provided with an elongated operating handle 20 preferably formed integral with the back thereof and is arranged to extend out through the slot 18 in the back of the ears and is bent over laterally about the one side of one of the ears 13, and is preferably arranged to extend around in a semicircle about one ear and so serve to effectively retain the guard in operative position in its mounting to continue to function even though these ears should be widely separated by some extraordinary force brought to bear thereon, and so still retain the pointed end of the pin-stem in the catch even under such extraordinary circumstances. This device is very simple and practical in construction and effective in its operation, and when its guard member is formed with its elongated encircling arm the element of safety in this catch is increased to a considerable extent.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A safety catch having a body portion formed of a pair of ears folded up from a common base and having a radially-disposed peripheral pin-tongue receiving slot, the inner face of each ear being provided with an annular groove, a ring-shaped guard rotor having a marginal pin-tongue receiving opening and slidably mounted in said groove, and an operating handle on said guard extending laterally over and about one side of one ear member to prevent the guard from becoming disengaged from its groove even though the ear members should become separated.

2. A safety catch having a body portion formed of a pair of side ears folded up from a common base and having a radially-disposed peripheral pin-tongue receiving slot, the inner face of each ear being provided with an annular groove, a peripheral slot in said ears communicating with said groove, a ring-shaped guard rotor having a marginal pin-tongue receiving opening and slidably mounted in said groove, and an operating handle on said guard extending out through said slot and folded over laterally to engage the side wall of one ear member to retain the rotor in operative position in its ear even though said ear members should become separated widely.

3. A safety catch comprising a body portion having a pair of ears with pin-tongue receiving slots therein, a guard rotatably mounted in said ears, and an operating handle on said guard extending over and about one of said ear members to prevent the guard from becoming disengaged from its ear member should the ear members become separated.

In testimony whereof I affix my signature.

EUGENE MOREHOUSE.
